UNITED STATES PATENT OFFICE

WILLIAM L. SCHELLENBACH, OF WYOMING, OHIO, ASSIGNOR TO THE AMERICAN TOOL WORKS COMPANY, OF CINCINNATI, OHIO, A CORPORATION OF OHIO

RADIAL DRILL

Application filed May 15, 1929. Serial No. 363,323.

This invention relates to radial drills of the type having a column pivotally mounted upon a stump, an arm vertically adjustable on the column, and a drilling head slidably mounted on the arm.

It is a recent tendency among the designers of radial drills to provide them with very long arms at any point along which the drilling head may be used. In positioning the drilling head over the exact spot to be operated upon, it is necessary for the workmen to swing the arm radially in relation to the base, which involves pivotally moving the column upon the stump, and it is also necessary to raise or lower the arm upon the column. The mechanism for clamping the column to the stump and the arm to the column must by necessity be in the general vicinity of the column and is therefore usually removed by at least several steps from the drilling head.

The inventor is fully aware of an English Patent No. 166,844 to James Archdale & Company and Joseph Jewsbury in which the arm clamp is operated by means of a lever attached to the head and splined to slide on an operating shaft disposed along the arm.

The object of this invention is to provide improved mechanism for performing both the column and arm clamping operations from the drilling head itself in order to eliminate not only waste motion on the part of the workmen but also to avoid the necessity of the workmen's attention being withdrawn from the immediate zone of work.

Various problems arise in providing mechanism responsive to this general concept due to the fact that these drilling machines are relatively ponderous and complicated from an engineering point of view, as a result of which it is requisite that certain mechanisms be located in certain general positions on the structure because of considerations foreign to the present problem which is to make the arm positioning mechanism operable from the drilling head.

For instance, it is necessary on these structures to have a column of relatively great diameter in order to provide sufficient bearing surfaces, staunchness of structure, and

freedom from vibration. It is also desirable to locate the arm positioning clamps on the column at points relatively removed circumferentially from the radius on which the arm extends.

It will, therefore, be observed that it is a specific object of this invention to provide mechanism accessible from the drilling head for operating clamping mechanism relatively spaced on the column from the arm.

Another object of the invention is to provide mechanism for accomplishing the purposes above set forth which will not interfere with other mechanism on the machine and which fulfil their functions with the economy of space and parts.

Further objects and advantages will be more fully set forth in the description of the accompanying drawings, in which:

Figure 1 is a front view of the radial drill incorporating the present improvements.

Figure 2 is a sectional view taken on line 2-2, Figure 1, illustrating the clamping mechanism for locking the arm to the column.

Figure 3 is a sectional view taken on line 3-3, Figure 2, further detailing the arm locking mechanism.

Figure 4 is a sectional view taken on line 4-4, Figure 1, illustrating the mechanism for clamping the column to the stump.

Figure 5 is an enlarged fragmentary front view of the lower end of the column, further illustrating the clamping mechanism.

Figure 6 is a sectional view taken on line 6-6, Figure 4, detailing the mounting of the crank sleeve for operating the column clamp.

Figure 7 is a sectional view taken on line 7-7, Figure 1, illustrating the connections from the horizontal operating shafts on the arm to the vertically disposed column clamping shaft and arm clamp operating cam sleeve.

Figure 8 is a sectional view taken on line 8-8, Figure 7, detailing the slidable connection of the respective operating levers fixed to the head on the shafts and the journaling of the shafts on the arm.

Figure 9 is a sectional view taken on line 100

9—9, Figure 8, further detailing the mounting of the clamp operating levers.

Figure 10 is an end elevation detailing the hanger for mounting the outer ends of the shafts on the arm.

5 Referring to the drawings, the base 1 has a stump 2 mounted thereon adjacent to one end. Upon the stump is rotatively mounted a column 3. This column 3 has an arm 5 slidably mounted thereon for rotative and vertical adjustment of the arm relative to the work mounted on the base.

6 A drilling head 6 is slidably mounted on the arm over the base so as to be adjustable 15 thereon to any point over the work. Extending from the bottom of the drilling head is the spindle 7. On the end of the arm opposite to the end on which the drilling head is mounted is an electric motor 8 which provides 20 the power for the machine. It is to be understood that the drill described is merely selected as disclosing one type of drilling machine to which the invention can be applied and that the invention can be applied to other 25 designs of radial drill as well.

7 A clamp 9 is provided at the bottom of the column to lock it to the stump in any desired position, and a clamp 10 is carried by the arm to lock it to the column in any desired position. These clamps will be herein-after described in detail.

8 Mounted upon the column and extending parallel thereto is a shaft 11. At the bottom of this shaft 11 there is a mechanical connection to the column clamp. As disclosed, this mechanical connection comprises a crank 12 secured to the shaft 11 and a crank arm 13 connecting the crank to the column clamping means.

9 For operation of the arm clamp, a sleeve 14 is loosely rotatively mounted on the shaft 11 and supported on the arm. This sleeve embodies a cam 15 which operates upon a bell crank lever 16 pivoted to the arm and this lever operates the arm clamping means.

10 The arm carries two shafts 17 and 18 parallel to it, these shafts traversing the drilling head. Manually operable levers 19 and 20 are splined to these shafts and pivotally secured to the drilling head so that they travel with the drilling head along the arm and can at any point be thrown to rotate the shafts which are parallel to the arm. At the inner ends of these shafts are cranks 21 and

22. The vertically extending shaft 11 is provided with a crank 23 which is secured to the arm and splined to the shaft so that it travels up and down with the arm and can be operated to rotate the shaft 11 at any position of the arm on the column.

11 The sleeve 14 about the shaft 11 has a crank 24 secured thereto. One drag link connection 25 links the crank 21 on the end of the upper shaft to the crank 24 extending

from the sleeve 14. Another drag link connection 26 links the crank 22 extending from the lower shaft to the crank 23 carried by the arm and splined to the shaft 11.

12 The result of the use of the mechanism above described is that the workman who is positioning the drill over the work at an exact point, can operate both the column clamp and the arm clamp from the drilling head without either moving or taking his attention from the work. If he wishes to operate the column clamps, he throws the lever 20 carried by the drilling head which rotates the shaft to which it is splined. This rotates the eccentric on the end of the shaft adjacent to the column which draws the drag link connection, operates the crank splined to shaft 11, rotates shaft 11 and the crank at the bottom of it which swings the lever connecting this crank to the column clamp, and operates the column clamp.

13 If the workman wishes to operate the arm clamp, he throws the lever 19 carried by the drilling head which turns the crank on its end, which pulls the drag link connection secured to said crank, rotates the sleeve 14 carried by the arm, moves the lever pivoted to the arm, and operates the arm clamp. It is to be understood, however, that various other types of connection can be substituted for those disclosed and above described, but that certain advantages inhere in the specific mechanism, which advantages will be more fully apparent from the ensuing detailed description of the various mechanical elements and organizations.

Column clamp

14 The enlarged lower end of the column, telescopically engaged over the stump, has its lower portion of split ring form, the split ring form portion being defined by a horizontal slot 27 circumferentially cut in the column immediately above the split. A draw pin or bolt 28 traverses the ears at each side of the split, and is provided upon one end with a nut 29. A washer 30 is placed between the nut and the adjacent ear. The head end of this draw pin extends beyond the other ear.

15 The head end of the draw bolt is pivotally connected to the crank lever or arm 18 which extends over to the column clamp from the vertical shaft 11. This end of the lever is slotted to receive the draw pin head, and a pivot pin 33 passes through the bolt head and lever. This end of the lever is provided with a camming end 34 which abuts against a washer 35 on the bolt and against the ear, so that when the end of the lever adjacent to the shaft 11 is moved away from the column, the lever cams on the portion abutting the washer and tends to draw the ears together which binds the column to the stump, since the portion of the column below the circumferential slot has the requisite degree of flexibility.

16 The lower portion of the column is provided with a slot 36 which extends circumferentially around the column, and a draw pin 37 is provided with a head 38 which is slotted to receive the pivot pin 33, and a washer 39 is placed between the head 38 and the pivot pin 33. The draw pin 37 is secured to the column by a nut 40.

- The lower end (see Figure 6), of the shaft 11 has a sleeve 36 splined to it by means of a pin 37 extending radially from the shaft into an axial slot 38 in the sleeve. This sleeve has, at its bottom, a head from which extends the crank pin 39. The lever 13 is connected to the crank pin by means of a connecting link 40 pivotally secured between the crank pin and the lever.
10. The sleeve 36 surrounding the shaft end is journalled in a bracket 41 which is secured to the column, near its bottom, by means of screws. The head at the lower end of the sleeve is provided with a circumferential groove 42 in its periphery in which is disposed a packing ring 43 engaging the bore of the bracket 41. Within the bracket and about the sleeve are two spaced ball bearings 44-44 seated in counterbores of the bracket.
11. Above the top ball bearing is a retaining collar 45 which is screw-threaded on the sleeve and set by means of a spring clip 46. This collar is also provided with a peripheral groove in which is disposed a sealing ring 47.

Arm clamp

As disclosed, the portion of the arm about the column is split. At the top and the bottom of this portion of the arm and adjacent to the split portion are sets of opposing ears 48. Each pair of opposing ears is traversed by a screw 49, the head of which is countersunk in one ear and which has a nut 50 on its other end. By means of this screw and nut arrangement, the appropriate residual tension is imparted to the ring. The nuts 50 are set to permit the ring to spread so that the arm is free to be moved. Each pair of opposing ears is also traversed by a draw bolt 51, each bolt being provided with a nut 52 on its end on the side of the ears away from the clamp operating mechanism. The other ends of these clamping members are headed and these heads 53 have conical ends seated in conical depressions in levers 54 which extend toward the middle portion of the ring, vertically speaking.

Between the ends of these levers and the ears are washers 55 through which the draw bolts pass. Therefore, when the other ends of these levers 54 are moved in a direction away from the operating mechanism and toward the split of the ring, they rock upon the washers and exert pulling influence upon the draw bolts, forcing the ears together, and binding the arm to the column.

These levers 54 are operated by a mechanism disposed in a casing 56 which is secured to the arm by means of screws. This bracket is traversed by the vertical shaft 11. The sleeve 14 which surrounds the shaft 11 and which operates the arm clamp is journalled in this bracket by means of ball bearings 57-57, one mounted in the top wall of the bracket and one in the bottom wall of the bracket.

The crank arm, by means of which this sleeve is connected to the shaft extending along the arm, is secured on the sleeve below the casing 56. The ball bearings are held in place by means of closure plates 58-58 secured to the walls of the casing 56.

The sleeve within the bracket embodies a cam 15 which engages a cam roller 59 mounted on one end of the bell crank lever 16 pivotally secured within the bracket. The other end of this bell crank lever abuts a plunger 61 mounted within the bracket, and on the other end of this plunger is disposed an element 60, having upper and lower radial flanges. The adjacent ends of the levers 54 enter the easing 56 adjacent to this flanged element and each engages a respective flange thereof.

In order to provide appropriate adjustment, a stud 62 is screw-threaded into the end of the flanged element and abuts the end of the plunger, mounted in the element. This bolt can be secured in any desired position by means of a lock nut 63 carried by it on the outside of the flanged element. In operation, the turning of the sleeve mounted upon the vertical shaft 11 causes the cam to rock the bell crank lever which forces the plunger in the direction of the clamp itself, which causes the flanged member to actuate the levers 54 extending from the bosses and force them toward the split in the ring, which operates the clamp, and binds the arm to the column.

Connection to drilling head

Extending downwardly from the bottom of the drilling head is a lever supporting element 64 through which the shafts parallel to the arm extend. The manually operated levers 19, 20, are splined each to a respective shaft, each hand lever being provided (see Figure 8) with a sleeve 65 which extends through the supporting member and is held pivotally to it by means of a retaining nut 66 on the opposite side of the supporting member from the extending lever portion. These hand levers therefore travel with the drilling head and are pivotally connected to it.

On the inner end of the arm adjacent to the column a shaft hanger 67 is secured by means of screws 68. This bracket provides journals for the inner ends of the said horizontal shafts. The outer ends of the horizontal shafts are journalled in a hanger 69, depending from the extreme outer end of the arm. On the inner end of each shaft a headed sleeve 70 is secured, and ball bearings 71 are disposed between the head and the hanger, as illustrated in Figure 8. On the other ends of these sleeves and on the opposite side of the hanger from the ball bearings, retaining nuts 72 are screwed to hold the sleeves and shafts against longitudinal displacement. Extending radially from the

ends of each flanged collar are cranks 21, 22, each having a pin 73 on its end. As disclosed in Figure 8, these pins are horizontally disposed. Pivoted on these pins are the drag links which operate the mechanism centering on shaft 11.

The links are each connected to the pins 73 by means of a universal joint. A yoke 74 on each link is secured to a collar 75 rotatably mounted on a respective pin 73 by means of pins 76 radially extending from the collar. The connection of the links to the levers on the shaft 11 is also universal, there being a yoke 77 engaging radial pins 78 in the head of a rotatable bolt 79 depending from each lever on the shaft 11.

It will thus be observed that the entire connection of the links is a universal connection since the drag links pivot vertically in relation to the cranks on the end of the horizontal shafts, and pivot horizontally in relation to the cranks carried by the sleeve 14 and the sleeve splined to the shaft 11. Therefore, as before described, the hand levers 28 upon the drilling head respectively operate the arm clamp and the column clamp.

The mechanism above described is very simple considering the result accomplished.

The parts are relatively inexpensive to manufacture and the design is such that reasonable tolerance in dimensions is permitted. Furthermore, the mechanism is readily lubricated, involves but little friction, due to the presence of numerous ball bearings, and is positive in its operation.

Having described my invention, I desire to be limited only by the ensuing claim:

In a radial drill of the type having a column pivotally mounted upon a stump, an arm vertically adjustable on said column, and a drilling head slidably mounted on said arm, mechanism operable from the head for clamping the column to the stump and the arm to the column, said mechanism, comprising, a vertical shaft carried by the column, a crank disposed on the arm and splined to said shaft, a sleeve mounted on the arm above said crank, said sleeve surrounding said shaft and rotatable upon the same axis, a clamp carried by said column, and adapted to secure it to said stump, a crank on said vertical shaft near the bottom of the column, mechanical connection between said clamp and said latter crank whereby the rocking of the shaft clamps and unclamps the column, a clamp carried by the arm adapted to clamp it to the column, a cam carried by said sleeve mounted on the arm, mechanical connection between said arm clamp and the cam carried by said sleeve whereby the rocking of said sleeve clamps and unclamps said arm, two horizontal shafts carried by said arm, said shafts traversing the head, two levers mounted in the head, one splined to each shaft, a crank on

the end of each horizontal shaft adjacent to the column, a drag link connection between the crank on one horizontal shaft and the crank splined to the vertical shaft carried by the column, so that the rocking of one shaft causes a rocking of the other to operate the column clamp, and a drag link connection between the crank on the other horizontal shaft and the sleeve mounted on the arm, so that rocking of the second shaft rocks the sleeve to operate the arm clamp.

In witness whereof, I hereunto subscribe my name.

WILLIAM L. SCHELLENBACH.
